CARPET CLEANER PICKUP HEAD

Judson O. Jones, 17 Inglewood Drive,
Greenville, S.C. 29607

Filed Feb. 6, 1970, Ser. No. 21,302

Term of patent 14 years

Int. Cl. D15—07

U.S. Cl. D49—17

Fig. 1.

Fig. 2.

FIG. 1 is a front perspective view of a carpet cleaner pickup head embodying my new design, and

FIG. 2 is a perspective view of the carpet cleaner pickup head taken from the rear of FIG. 1 further illustrating my new design.

The broken lines are for illustrative purposes only.

I claim:

The ornamental design for a carpet cleaner pickup head, substantially as shown and described.
